United States Patent Office.

JAMES ALBEE, OF BOSTON, MASSACHUSETTS, ASSIGNOR TO MOSES POND AND COMPANY, OF SAME PLACE.

Letters Patent No. 79,294, dated June 30, 1868.

IMPROVEMENT IN HOT-AIR FURNACES.

The Schedule referred to in these Letters Patent and making part of the same.

TO ALL PERSONS TO WHOM THESE PRESENTS MAY COME:

Be it known that I, JAMES ALBEE, of Boston, in the county of Suffolk, and State of Massachusetts, have invented a new and useful Improvement in Air-Heating Furnaces; and I do hereby declare the same to be fully described in the following specification, and represented in the accompanying drawings, of which—

Figure 1 is a front elevation, and

Figure 2 a vertical section of my improved furnace.

Figure 3 is a horizontal section, this latter section being taken through the horizontal flue N which supports the evaporating-pan or vessel.

Figure 4 is another vertical section, it being taken through the upright-flue pipe at the front of the furnace.

Figure 5 is a horizontal section, taken through the door L of the throat K of the chamber or drum b', which surrounds the fire-pot.

In such drawings, A denotes the fire-pot, B the grate, and C the ash-chamber; the latter being provided with a throat, D, having a door, E.

The fire-pot A opens at top into a drum or smoke-chamber, F, which is provided with a series of pipes, G G, &c., which extend from its top to and through its bottom, and are arranged nearly around the fire-pot. These pipes project below the bottom of the drum F, and to and through a segmental ring or air-deflector, H, arranged concentrically within a case, I, within which the drum, the fire-pot, and ash-chamber are placed.

The deflector H directs the air, which may enter the bottom of the case I, to the mouths or lower open ends of the pipes G, and also into the space which is between the fire-pot and the extension, G', of the pipe G, below the drum F. The said pipes G are open at their upper as well as at their lower ends.

Within the drum F, and on the flanks of its throat K, such throat having a door, L, are two other pipes, M M, which reach nearly to the top of the drum; are open at their upper ends, and go down through the bottom of the said drum, and open into a horizontal connection-flue, N, resting on the throat of the ash-chamber.

This connection-flue, at its two ends, opens through the case I, on opposite sides of the evaporating-pan or throat d' of the case I. One end of the said flue N is closed by a cover, e, and the other opens into a conduit, f, that has a register or door, g, on its front end, and projects from the case I, in manner as represented. The inner end of the conduit is inserted into and fits to the mouth of the connection-flue, the other mouth of such flue being adapted to receive the conduit in like manner. A flange, h, on the conduit, by contact with the case I, limits the distance of entrance of the conduit into the flue N.

A pipe, O, leads vertically out of the top of the conduit f, and, near the top of the drum F, receives a branch-pipe, P, provided with a damper, z. This branch-pipe is the "direct-draught" pipe. It opens out of the drum, and into the smoke-discharge pipe O.

The pipes M M are the indirect-draught pipes, and are used to cause the smoke and volatile products of combustion to flow into and through the connection-flue N, the object being to heat it so as to impart heat to a water-vessel or evaporating-pan, P, when resting on the top of the flue N. This vessel may be either introduced into or removed from the case I through its throat d', such throat being provided with a door, l.

By having two mouths to the flue N, I am enabled to introduce the conduit f into either, it being sometimes more convenient to use it in one than in the other, in which case the latter should be stopped by the cover e, which, for such purpose, should be inserted in it.

The flue N may have but one pipe, M, which may enter the flue near either of its ends, so as to cause the smoke and gases to flow either through or into the said flue; but I prefer to have two of such pipes, and to provide one of them, that is, that one which is next the conduit f, with a cross-partition, n, having a hole, o, through it, of such diameter as will cause the smoke to pass in or about in equal quantities down the two pipes M M. In the place of the said cross-partition and its hole, I can employ a damper in the pipe, the same enabling me to regulate to better advantage the amount of smoke going through the two pipes.

The air to be heated in the case I enters its open bottom, impinges against the deflector H, and part of it passes into and through the pipes G' G. The rest of it rushes into the space between the pipe-extensions G' and the fire-pot, and thence up into the space surrounding the smoke drum, the said air being heated in the mean time by heat radiated from the surfaces of the said drum, the pipes, and the fire-pot. The air so heated may be taken from the case I, by one or more conduits leading out of the top of the case.

I make no claim to the arrangement of pipes G' G with the drum F and case I; nor do I claim the arrangement and combination of the air-conduit f, the escape-pipe O, and the pipe h', provided with a damper, i, and one pipe M, with the drum F, its throat, and fire-pot.

I claim as my invention, the following, viz :

The arrangement and combination of the flue N with either or both the pipes M, the fire-pot A, the drum F, the conduit f, the escape-pipe O, or its branch-pipe h', provided with a damper, as described, the case I being furnished with a throat or opening for the passage of the evaporating-pan P to and from the top of the flue N, as set forth.

I also claim the arrangement and combination of the deflector H with the case I, the fire-pot A, the drum F, the series of pipes G, and their extensions G', arranged with the drum and the fire-pot, as specified.

I also claim the combination of the damper, or the partition n, having a hole, o, as described, with the two pipes M M, and the flue N, arranged with the fire-pot, the drum, and the case, and combined with the conduit f and the escape-pipe O, as set forth.

I also claim the arrangement of the evaporating-pan and its throat with the flue N and the fire-pot.
